THOMAS J. FINNERTY, OF PHILADELPHIA, PENNSYLVANIA, ASSIGNOR OF ONE-HALF
TO CHARLES A. JACKSON, OF RIDGEWOOD, NEW JERSEY

WINDOW DEVICE

Application filed May 19, 1928. Serial No. 278,976.

This invention relates to means for controlling the opening and closing of windows, transoms or the like, particularly of the pivoted type, and for holding the windows in any desired degree of open position.

One object of the invention is to provide improved means whereby operation of the window may be effected with ease and also simplicity both as to the mechanism employed 10 and the mode of operating same.

A more specific object is to provide improved means adapted to automatically hold the window in any position to which it is opened and to have this means adapted for 15 release to permit automatic closing of the window, this being specifically accomplished by the provision of telescopic members one of 20 which has a spring operated pivoted friction element for engagement with the other member.

Other objects and advantages will be seen from the following description of the accompanying drawings in which;

Fig. 1 is a perspective of a window arrangement showing my improved device applied thereto.

Fig. 2 is an enlarged perspective of my device applied to a fragmentary portion of a window and sash, and

Fig. 3 is a fragmentary section showing the locking element in detail.

To obtain a device which is not only efficient in operation but is also simple in design and therefore inexpensive to manufacture, 35 I provide two telescopic or extensible members 1 and 2 respectively pivotally connected to brackets 3 and 4 carried on the stationary window frame 5 and movable window sash 6. The window herein disclosed is of the type pivoted on a horizontal axis 7 above its center of gravity whereby it may close by itself if not otherwise held. The invention as will herein be seen is also applicable to other types of windows.

A friction element 8 is pivotally supported at 9 to a collar 10 in turn threadedly connected to member 1 which may be a pipe as shown or of other suitable construction adapted for cooperation with a second member such as 2. 50 Rod 2 passes through a slightly enlarged

opening 11 in the friction element 8, the wall of the opening being in constant frictional contact with rod 2 due to a compression spring 12 disposed in a recess or collar 10 and engaging small projections 13 carried on each 55 side of element 8.

Thus it is seen that due to the pivotal connections to sash 6 and frame 5 being on opposite sides of the pivot 7 the window when moved to any open position as by a pull chain 14 will cause rod 2 to slide inwardly of pipe 1, the friction element 8 automatically releasing itself although the instant the pull on chain 14 is stopped, friction element 8 immediately grips rod 2 and holds the window 65 in position.

To close the window, friction element 8 need only be pulled downwardly against spring 12 as by a chain 15 connected to a suitable handle 16 which extends from element 8, the chain being operable from any remote point which may be convenient to reach. This releases any frictional contact or binding action and permits the window, due to its offset pivot 7, to close by gravity.

The angle of inclination of element 8 to rod 2 and the tension of spring 12 is such that any holding or binding action is readily released or overcome only by pull on chain 14.

If conditions are such that closing of the windows must be assisted there is provided a compression spring 17 interposed between the end of rod 2 and the lower pivot pin 18 which extends transversely through pipe 1. By the particular positions of the brackets 3 and 4 spring 17 will at all times and for any open position of the window be adapted to exert a closing force on the window.

A further functionally cooperating arrangement of parts resides in having brackets 3 and 4 and the related elements so disposed that the pivot point of the upper bracket 4 is adapted to move through 45 degrees on each side of the window pivot 7 and that when the window is in its wide open or horizontal position bracket 4 engages a cushioning spring 19 thereby providing a stop for positioning the window at a predetermined point. Such a feature is desirable so that all opened windows may have the same degree of 100

opening at least in one position and without any conscious effort as to aligning the windows when opening a series of them.

As is usual in windows of the type herein disclosed chain 14 is adapted not only to pull the windows open but also to release a usual snap catch which locks the window in closed position, the snap being diagrammatically shown as 21. The chain passes upwardly therefrom over a suitable guide 22 and down so that one pull on the chain, both releases catch 21 and pulls the window open.

While the windows shown have a vertical sash member in the same plane with a vertical part of the stationary frame thereby permitting both brackets 3 and 4 to lie in the same plane and without necessitating any bends in the members such as 2 it will of course be understood that such bends or alterations may be made to adapt the device for different conditions of use.

However, under any conditions it is seen that the device is very simple in operation and construction, requires very little space, is relatively inconspicuous, is free from constituting an obstruction through the open window, and can be installed quickly and easily upon any existing window installations of the type such as disclosed.

Various modifications may be made in the construction and arrangement of parts but which would fall within the scope of the appended claims.

I claim:

1. The combination comprising a stationary vertical window frame member, a window sash member pivotally supported thereby, and means for automatically holding the window in substantially any position to which it may be opened by manually pulling directly thereon, including a rod pivotally connected to one of said members, and a yieldably held releasable friction member adopted to engage said rod and being pivotally supported by the other of said members, said friction member being so disposed relative to said rod that opening movement of the window tends to move said friction member in a direction to reduce frictional contact.

2. The combination comprising a stationary window frame member, a vertical window sash member pivotally supported thereby, and means for automatically holding the window in substantially any position to which it may be opened by manually pulling directly thereon, including a rod pivotally connected to one of said members, a releasable frictional element supported by the other said members and having an opening through which said rod passes for frictional engagement therewith, said frictional element being wholly movable in only one direction to be released and in the opposite direction for frictional contact, and a spring

for pressing said element into said frictional contact, said rod and frictional element being so arranged that upon release of said element said window closes automatically.

3. A window controlling device comprising a pair of brackets, a pipe pivotally connected to one thereof, a rod having telescopic connection with said pipe and pivotally connected to the other of said brackets, a collar carried by an end of said pipe, a friction member pivotally supported by said collar and having an opening through which said rod passes for frictional contact therewith, and a spring interposed between said collar and friction member for urging said friction member into contact with said rod.

4. A window controlling device comprising a pair of brackets, a pipe pivotally connected to one thereof, a rod having telescopic connection with said pipe and pivotally connected to the other of said brackets, a collar carried by an end of said pipe, a friction member pivotally supported by said collar and having an opening through which said rod passes for frictional contact therewith, a spring interposed between said collar and friction member for urging said friction member into contact with said rod, and a spring interposed between the end of said rod and the pivoting end of said pipe for urging said rod outwardly.

5. A window controlling device comprising, in combination, a pair of brackets, an elongated member pivotally connected to one of said brackets, a rod having overlapping slidable connection with said elongated member and pivotally connected to the other of said brackets, a friction member pivotally supported by said elongated member and having an opening through which said elongated member passes for frictional contact therewith, and means for yieldingly urging said friction member into contact with said rod.
